UNITED STATES PATENT OFFICE.

ELMER S. BILLS, OF CHICAGO, ILLINOIS, ASSIGNOR, BY DIRECT AND MESNE ASSIGNMENTS, TO HARMONY SPRING CUSHION CO., A CORPORATION OF ILLINOIS.

SPRING-CUSHION CONSTRUCTION.

1,382,462.

Specification of Letters Patent. Patented June 21, 1921.

Application filed February 5, 1919. Serial No. 275,060.

To all whom it may concern:

Be it known that I, ELMER S. BILLS, a citizen of the United States, and a resident of Chicago, in the county of Cook and State of Illinois, have invented certain new and useful Improvements in Spring-Cushion Construction, of which the following is a specification.

My invention relates to spring cushion construction and is in the nature of an improvement upon the invention set forth in co-pending application Serial No. 247,316. The primary object of the present invention is to provide an improved combination of cushion springs and spring pockets whereby the manufacture of cushions may be simplified and cheapened. Another object is to combine in a cushion the known advantages of flexible spring pockets with the advantages of spring construction and compact arrangement set forth in said co-pending application. A further object is the provision of an improved combination of coiled springs and pockets whereby the pockets converge and are secured together at a common center. A still further object lies in the provision of an improved combination and arrangement of springs and pockets wherein said pockets are connected into a series comprising a single spring containing envelop which may be folded to form a complete cushion the springs of which are very compactly arranged. Another object is the provision of an improved type of envelop for cushion springs in which are embodied simplicity in construction and facility in handling.

Other objects and advantages of the invention will appear from the following description, taken in conjunction with the accompanying drawings which form a part of this specification and illustrate the preferred embodiment of the invention.

In the drawings:

Figure 1 is a perspective view of a spring cushion constructed in accordance with the principles of the present invention, the upper surface showing diagrammatically only the arrangement of the springs and the disposition of the upper portions of a band and a strip which are sewed together, surround each of the springs, and extend throughout the cushion.

Fig. 2 is a fragmentary corner view in

perspective of the actual assembly of the 55 cushion, showing the disposition of the seams of the envelop.

Fig. 3 is a top plan view of a unit for the construction of cushions from springs pocketed in accordance with this invention. 60

Fig. 4 illustrates in perspective the construction of my improved envelop and the mode of assembling the springs therein, one of the springs being shown in position for insertion into its pocket. 65

Referring to Fig. 4, numeral 10 indicates generally a flat band of cloth or like material upon which is fulled at regularly spaced intervals a strip generally indicated at 11. The strip may be fulled upon the 70 band in any desired manner, though I prefer to do this by initially folding the strip transversely along the lines 12, sewing it to the band along the regularly spaced transverse lines 13, and then forming near the 75 longitudinal edges of the strip, midway between the stitchings 13, the transversely extending plaits 14. Fig. 4 shows four complete spring receiving pockets 15, 16, 17 and 18, made from the band 10 and strip 11 and 80 forming a connected series which will be herein termed an envelop 19. Pocket 18 is open at both ends and shows the condition of a pocket when the strip is first stitched transversely to the band; at the lower end 85 of pocket 17 are shown the folds made in forming plait 14; at the lower end of pocket 16 the plait has been formed and the longitudinal edges of the band and strip sewed together along line 21 to close the bottom of 90 the pocket and form an edge seam generally indicated at 22. A prism-shaped coiled spring 23, of the type set forth in my said co-pending application, is provided for each pocket of the envelop. In end contour this 95 spring is an isosceles right triangle having the 90° apex angle 24 and the 45° base angles 25 and 26. One of these springs is shown fragmentarily in dotted lines in pocket 15 of Fig. 4, which pocket has been 100 completely closed by the plaiting of the upper edge of strip 11 and the sewing together of the upper longitudinal edges of the band and strip to form the upper edge seam 22. The springs 23 are preferably under a slight 105 compression when inclosed in the envelop pockets, and their tendency to expand draws the seam 22 at its plaited portion inwardly

across the end of the spring substantially to the axis thereof, as seen in Figs. 2, 3 and 4, the seam, however, intersecting the base angles 25 and 26 of the spring and at these 5 points standing in the plane of the major portion of the flat band 10. While the tendency of the spring to expand within the pocket, and the consequent pull exerted across its apex 23 by strip 11 draws a small 10 portion of band 10 over the ends of each spring, the greater portion of the band remains in flat, vertical, angularly related planes when envelop 19 is folded up to form the cushion.

15 Fig. 3 illustrates in plan view a four-spring unit which may be formed from the envelop shown in Fig. 1, though I prefer to construct cushions by the use of a single long envelop such, for example as that shown in 20 Figs. 1 and 2, containing a long connected series of many pocketed springs, forty-eight in this instance. At the left of pocket 18 and at the right of pocket 15 in Fig. 4 it will be seen that two parallel rows of stitching 25 18 are provided between adjacent pockets. These parallel rows of stitching may be placed between any desired pair of adjacent pockets, and they are spaced from each other slightly in order that the strip 30 and band may be cut across between these pockets. Thus a series of four pocketed springs may be cut from a much longer envelop for the formation of the unit shown in Fig. 3. In the latter figure the meeting 35 base edges of pockets 15 and 18 are stitched together as at 26^a to hold the four pockets 15, 16, 17 and 18 and their springs in the unit formation.

The preferred form of cushion construction is illustrated in Figs. 1, 2 and 4 wherein an envelop comprising a single connected series of pocketed springs is folded upon itself to form the whole spring body; the 40 springs fitting against each other in flat side 45 contact to form a solid body of springs. Cushions of any desired size may be made in this manner, the size determining the number of springs and the length of envelop to be employed. To show the disposition in vertical planes of the major portions 50 of band 10 and strip 11 and their continuity 55 throughout a complete cushion, the band and strip have been shown diagrammatically in the upper surface of Fig. 1, the seams 22 being disregarded. Also, for a clear understanding of the spring arrangement, the pocketed springs used in the cushion of Fig. 1 have been numbered successively from 101 to 148 in the order in which they stand in 60 their single envelop, the latter being constructed as shown in Fig. 4.

A great advantage in the construction of envelop 19 lies in the fact that as seen in Fig. 2, seams 22 intersect the base angles 65 of each spring at the ends of the pockets

and that the lines of stitching 18 meet the seams 22 and lines of sewing 21 at these angles. Thus the strongest portions of the envelop converge to a common center 27 wherever a plurality of these base angles 70 meet. At each of these centers 27 a tie member 28, preferably a stout cord, is used to sew or otherwise fasten together the four or eight portions of seam 22 that so converge, the result being that the pocketed springs 75 are very firmly and compactly held together as a unitary cushion body.

Upper and lower frame members 28 and 29 are provided at the top and bottom respectively of the cushion body just described, and are secured thereto by cords 80 sewed through the envelop 19 and about the frames this cord being preferably passed through each center 27 adjacent the frames.

Under the weight of a person sitting on 85 the cushion the springs affected by the weight are compressed with relation to adjacent springs. The envelop 19 quiets the passage of the coils of one spring across those of others, yields with the springs, prevents axial bending of the central portions of the springs, and holds their ends from separation or interengagement.

I claim:

1. In spring cushion construction, the 95 combination with a single band disposed in angularly related planes that join each other along parallel lines and comprise one side of a continuous envelop for the springs of a complete cushion, of a complementary 100 envelop side for the band comprising a strip following the band, fulled thereon at regularly spaced intervals along its longitudinal edges and sewed to the band along its edges and along transverse lines between said 105 fulled portions to form spring pockets, and prism-shaped springs positioned one in each pocket.

2. In spring cushion construction, the 110 combination with a single band disposed in angularly related planes that join each other along parallel lines and comprise one side of a continuous envelop for the springs of a complete cushion, of a complementary 115 envelop side for the band comprising a strip following the band, fulled thereon at regularly spaced intervals along its longitudinal edges and sewed to the band along its edges and along transverse lines between said 120 fulled portions to form spring pockets, and a prism-shaped coiled spring having the end contour of an isosceles right triangle positioned in each pocket with its base in flat contact with said band.

3. In spring cushion construction, the 125 combination with a flat band, of a strip fulled upon the band and secured thereto along its edges and along regularly spaced transverse lines to form spring pockets, and a prism-shaped coiled spring having the end 130

contour of an isosceles right triangle positioned in each pocket with its base in flat contact with said band.

4. In a spring cushion, the combination of; a continuous envelop comprising a substantially flat band, and a strip fulled upon the band and sewed thereto to constitute a series of parallel connected spring receiving pockets; a prism-shaped coiled spring having the end contour of an isosceles right triangle positioned in each pocket with its base in flat contact with said band; said envelop being folded on parallel lines to bring said springs into compact association; and a pair of spaced parallel frame members surrounding the folded envelop and secured to said band.

5. The combination of a substantially flat band, a strip sewed to the band along transverse lines to define parallel spring receiving pockets and along its edges to close the ends of said pockets and form a seam, said band and strip forming an attenuated envelop, a prism-shaped coiled spring in each pocket, said envelop being folded to bring the springs and pockets into close association with a plurality of the folds of said seam meeting at a common center, and means for securing said seams together at said center.

30 6. The combination with a plurality of coiled springs angular in end contour and grouped to bring one angle of each into close association with an angle of each of the others at a common center, of a pocket for each spring comprising a seam traversing the end of the spring, said end seams meeting at said common center, and means for securing said seams together at said center.

7. The combination with a plurality of identical coiled springs each having the end contour of an isosceles right triangle, of a pocket for each comprising a band and a strip sewed together to form a seam traversing the end of the spring and intersecting the base angles thereof, said springs and pockets being grouped with one base angle of each meeting a similar angle of each of the others about a common center, and means for securing said end seams together at said center.

50 8. The combination with a plurality of identical coiled springs each having the end contour of an isosceles right triangle, of a pocket for each comprising a band and a strip sewed together to form a seam traversing the end of the spring and intersecting the base angles thereof, said springs and pockets being grouped with one base angle of each meeting a similar angle of each of

the others about a common center, and means for securing said end seams together at said center, said pockets being joined along their longitudinal edges to form a continuous spring-holding envelop which is folded at said common center.

65

9. The combination of an envelop comprising a band, and a strip fulled thereon, stitched to the band transversely and sewed thereto along its longitudinal edges to form a series of spring-receiving pockets; and a coiled spring in each of the pockets; said envelop being folded to group the pocketed springs compactly about a common center, the seams of said stitching and sewing intersecting at said center.

75

10. The combination of an envelop comprising a substantially flat band, and a strip fulled thereon, stitched to the band along transverse lines and sewed thereto along its longitudinal edges to form a series of spring-receiving pockets and edge and transverse seams; a prism-shaped coiled spring triangular in cross-section positioned in each pocket with its base in flat contact with the band; said envelop being folded to group one base angle of each of a plurality of said springs about a common center, said edge and transverse seams intersecting each other at said center; and a tie member at said center securing the group of springs together by connection with said intersecting seams.

80

11. The combination of an envelop comprising a substantially flat band, and a strip fulled thereon, stitched to the band along transverse lines and sewed thereto along its longitudinal edges to form a series of spring-receiving pockets and edge and transverse seams; a prism-shaped coiled spring having the end contour of an isosceles right triangle positioned in each pocket with its base in flat contact with the band; said envelop being folded to group one base angle of each of a plurality of said springs about a common center; and a tie member at said center securing the group of springs together by connection with said intersecting seams.

95

12. In a spring cushion, the combination with a plurality of coiled springs, of an envelop therefor comprising a band and a strip which are sewed together to form longitudinal edge seams, said envelop being folded to cause folded portions of said edge seams to converge at a common center, and a tie member securing said seams together at said center.
